(57) **CLAIM**

The ornamental design for a planter bag, substantially as shown and described.

DESCRIPTION

FIG. 1 is a top perspective view of a planter bag in accordance with the present invention;

FIG. 2 is a bottom perspective view thereof;

FIG. 3 is a top plan view thereof;

FIG. 4 is a bottom plan view thereof;

FIG. 5 is a side view thereof;

FIG. 6 is an opposite side view thereof;

FIG. 7 is a side view rotated 90 degrees thereof;

FIG. 8 is a side view rotated 90 degrees thereof;

FIG. 9 is a top perspective view of another embodiment of a planter bag in accordance with the present invention;

FIG. 10 is a bottom perspective view thereof;

FIG. 11 is a top plan view thereof;

FIG. 12 is a bottom plan view thereof;

FIG. 13 is a side view thereof;

FIG. 14 is an opposite side view thereof;

FIG. 15 is a side view rotated 90 degrees thereof; and,

FIG. 16 is a side view rotated 90 degrees thereof.

The broken lines showing the remainder of the horticultural bag are directed to environment. None of the broken lines form part of the claimed design.
